ENGINE STARTING MECHANISM

Harold D. Hoekstra, Rockville, Md.

Application February 19, 1941, Serial No. 379,705

1 Claim. (Cl. 185—39)

1

My invention relates in general to engine starting mechanisms and in particular to a starter of the spring motor type adapted for use in cranking internal combustion engines of the airplane type.

An object of my invention is to provide a starter of this type which will be light weight, simple, and inexpensive, being particularly adapted for use with low and medium powered aircraft.

Another object is to provide a starter of this type in which a varying amount of energy may be stored (at a rapid or slow rate) and which energy may be expended as desired by the operator.

It is also the object of this invention to provide a starter which canot be wound to an excessive degree either by the operator, or by an engine back-fire.

Still another object of my invention is to provide a novel release and clutching means which will insure ready release and positive clutching action and which will be free-running with no rubbing action when disengaged.

A further object of this invention is to provide means whereby the efficient and desireable compression type spring with its rectilinear motion may be utilized to secure rotary motion.

Another object of this invention is to provide safety means to harmlessly dissipate the stored energy in the starter in the event of clutch failure or inadvertent release.

Other objects of the invention will be manifest from the following description of the preferred form of the invention, taken in connection with the accompanying drawings, wherein

Fig. 1 is a side elevational view of an airplane engine starter constructed in accordance with the present invention, illustrating its application to an engine, the latter being fragmentarily shown;

Fig. 2 is a longitudinal sectional view of the starter motor, portions thereof being broken away to disclose details;

Fig. 3 is an end elevational view of the starter motor, and associated appurtenances, the latter being fragmentarily shown;

Fig. 4 is a top plan view of a starter made in accordance with my invention, the starter motor being fragmentarily shown;

Fig. 5 is a fragmentary side elevational view of my starter showing in detail portions of the "wind-up" mechanism;

Fig. 6 is a sectional view taken on line 6—6 of Fig. 5 looking in the direction of the arrows, showing the motor casing engaging spring in side elevation;

2

Fig. 7 is a fragmentary sectional view of the starter, showing to advantage the clutch with the rollers omitted;

Fig. 8 is a sectional view taken on the line 8—8 of Fig. 7, looking in the direction of the arrows, showing the clutch with rollers mounted in clutch cage.

Fig. 9 is a fragmentary elevational view of the starting motor drive shaft;

Fig. 10 is a fragmentary sectional view of a modified form of clutch, for use in the present invention, the rollers being omitted.

Fig. 11 is a sectional view taken on the line 11—11 of Fig. 10, looking in the direction of the arrows, showing this modified form of clutch in end elevation,

Fig. 12 is a fragmentary detail sectional view taken on the line 12—12 of Fig. 11, looking in the direction of the arrows, showing to advantage the modified form of roller, the latter being shown in side elevation, and

Fig. 13 is an elevational view of a tooth fragment of the worm showing a conventional form of thread superimposed thereon, in dotted lines, pressure and pitch lines being also illustrated thereon.

In order to illustrate the application of my invention I have shown in Fig. 1 a fragment of an airplane engine 15 and its crankshaft 16, a pilot's seat 17, and an engine starting mechanism, generally designated 18. The engine starting mechanism is operatively connected to the crankshaft 16, said starting mechanism being fastened or secured to the engine block by bolts 19.

My engine starting mechanism comprises a cylindrical shell 20 one end of which is closed, the opposite end being equipped with a housing 21, which latter, in conjunction with the shell 20, provides a casing for details of the starter mechanism hereinafter described. These details include a shaft 22 which extends axially through said shell and housing and has formed on the engine end an inner race 23 of a roller clutch.

On the shaft 22 a coarse pitch multiple thread 24 is provided and mating therewith a large diameter flanged nut 25. Formed on two sides of nut 25 are grooves 26 which mate with splines 27 formed in the shell 20 to prevent rotation of nut 25 while allowing translational movement thereof along the longitudinal axis of the housing. Compression springs 28 and 29, coaxial with shaft 22, react against the housing 21 and nut 25 and serve to store energy when nut 25 is displaced towards the engine end of starter mecha-

nism. Bearing 30 carries the thrust load from shaft 22 into housing 21. Fixedly attached to shaft 22 is worm wheel 31 which reacts with a worm 32 attached to shaft 33 as shown to advantage in Fig. 3. Shaft 33 is carried by a bearing 34 formed in a drum housing 35. Worm 32 and shaft 33 are rotatable, in one direction only, by the drum 36 of a drum housing 35 through a conventional ratchet and pawl mechanism 37 and 38 respectively. The pawls are engaged, for a manifest purpose, by springs 39 as shown to advantage in Fig. 5. Worm 32 and shaft 33 are rotated in a direction to cause rotation of worm wheel 31 in the "wind" direction as shown by the arrow in Fig. 3 by means of cable 40 passing around drum 36. Cable 40 is trained around pulley 41 and passes into the cabin or cockpit of the airplane and is there attached to handle 42. The handle 42 is positioned adjacent the seat 17 for convenient accessibility to the pilot for winding the motor of the starter mechanism, as shown in Fig. 1. The return rotation of drum 36 is accomplished by means of a torsion spring 43, the two ends of which are anchored in housing 35 and drum 36 respectively. The worm and housing assembly is rotatably mounted on bolt 43' which is anchored in boss 44 formed on shell 20, to permit disengaging worm 32 from worm wheel 31.

A basically conventional roller type over-running clutch, such as shown in Figs. 2, 7, and 8, is mounted in the engine end of the starter mechanism. The clutch comprises an outer race 45 which is attached to engine 15, inner race 23, and rollers 46. A novel arrangement is provided to prevent the rollers contacting the outer race 45 during the over-running or disengaged period. This consists of roller cage 47 with spring members 48, pin 49, slots 50 and 51 of the inner race 23 and cage 47 respectively, clutch rod 52, button 53, and spring 54. The rollers are kept free of the outer race 45, except when starting. The axial movement of clutch rod 52 is transformed into rotary motion by means of pin 49 and slot 50 in the inner race 23. Then by means of pin 49 and slot 51 in cage 47, the roller cage is rotated thus bringing the rollers out of engagement with outer race 45.

Another type of over-running clutch which has been found to work very satisfactorily is shown in Figs. 10, 11 and 12 wherein conical rollers 46' are employed and react between the inner race 23' and the conical outer race 45'. This type of over-running clutch permits direct axial movement of clutch rod 52 to engage or disengage.

The operation of the starting mechanism is as follows: To store energy or to wind-up the starter motor, the pilot or operator pulls handle 42 and cable 40 rotates drum 36 and the worm 32 which in turn rotates worm wheel 31 in the direction of the "wind-up" arrow shown in Fig. 3. Rotation of the worm wheel 31 turns the threaded shaft 22 and nut 25 is moved in a direction to compress springs 28 and 29. Storage of energy in the springs can be stopped at any point desired and it is impossible to compress springs 28 and 29 to an excessive degree through manual energy storage or through back-fire since the nut 25 travels off the threads of shaft 22 when a predetermined compression value is reached, as shown at 55 in Fig. 2. The ends of the threads on shaft 22 and in nut 25 may be rounded, as at 56 in Fig. 2, to avoid a "dead center" position, when the starter is fully wound, thus insuring positive, quick release for starting.

Starting is accomplished by depressing the starting pedal 57 in Fig. 1 which operates cable 58 and pulls down lever 59. Lever 59 is rotatably attached to bolt 43' by means of boss 44. Formed in lever 59, is slot 60 which mates with pin 61 anchored in housing 35. Spring 62 tends to rotate the lever 59 in a direction opposite to that produced by tension in cable 58 and acts to prevent unintentional release of the starting mechanism. Clutch engaging spring 63 is attached to lever 59 and through a portion of the travel of lever 59 bears upon button 53 depressing the same. As the button 53 is depressed, it operates to advance the clutch rod 52 and places the clutch in an operative position and at the same time lever 59, by means of pin 61 and slot 60, disengages the worm 32 from the worm wheel 31 thereby allowing the springs to utilize the stored energy and rotate the engine to be started.

In the event that the starter springs have been partially or fully compressed and the lever 59 is operated while the engine is running or if there is clutch slippage, the stored energy in springs 28 and 29 cannot be utilized in the usual manner and must be dissipated in some other manner to avoid damage to the starter. This is accomplished by means of a seal 64 attached to the flange of nut 25 thus forming an air buffer cylinder in shell 20, as shown to advantage in Fig. 2. A metering valve 65 is provided in shell 20, consisting of an orifice setscrew 66 to permit adjustment of the airflow therethrough and consequently to allow adjustment to the proper degree of buffing to prevent injury to the starting mechanism.

Preferably, as shown in Fig. 13, the threads of the worm 32 and worm wheel 31 have the meshing faces thereof rounded so that the pitch line is substantially as indicated at X while the pressure angle lines are as indicated at Y. This embodiment of the invention taken with the preferred location of bolt 43' in close proximity to the extension of the pressure angle line Y, whilst being a substantial distance from pressure angle line Z, permits reversibility in the "wind" direction, to prevent damage from reverse engine rotation due, for example, to back-fire during contact of worm wheel 31 and worm 32 because of sudden release of pedal 57 immediately after starting. It will be readily seen that the tendency of worm wheel 31 to rotate in the "start" direction shown on Figure 3 will, due to the shape of the meshing teeth on both worm wheel 31 and worm 32, exert a force substantially along the line Y of Figure 13. Since by specification bolt 43' is in close proximity to line Y extended, there is no appreciable tendency for the worm and drum assembly and the housing 35 in which they are mounted to pivot about bolt 43'. Hence the teeth will remain in mesh and the system may be considered irreversible. However, rotation of worm wheel 31 in the "wind" direction applies force to the worm 32 along a line normal to the mating teeth faces subjected to the force and hence displacing the worm 32 out of contact with worm wheel 31 by pivoting of housing 35 and its assembled components about bolt 43'. Hence, in this direction the system is reversible. As is well known to those versed in the art, spring 54, though it will tend to disengage the clutch upon release of pedal 57, will not normally have sufficient force to overcome clutch friction and hence the above described worm reversibility is necessary.

75 It is to be understood that various changes may

be made in the details of construction, proportion and arrangement of parts within the scope of the claim hereto appended.

What is claimed is:

A spring motor, means to store energy in the motor including a worm and worm wheel, the teeth of the said worm and worm wheel having faces on one side inclined at a greater pressure angle than the faces on the opposite side of the said teeth, the said worm being pivotally mounted with the pivot axis substantially parallel to the axis of the

said worm wheel and located in close proximity to the projection of a line passing through the pitch circle of the said worm wheel normal to the teeth faces having the lesser pressure angle and at the point of worm and worm wheel contact so as to permit relative translation between said worm and worm wheel substantially parallel to one pair of mating tooth faces and at an appreciable angle to the adjacent pair of mating tooth faces.

HAROLD D. HOEKSTRA.
